UNITED STATES PATENT OFFICE.

JAFEW S. VAN BUREN, OF ALBANY, NEW YORK.

DESIGN FOR A WATER-FRONT FOR STOVES.

SPECIFICATION forming part of Design No. 33,148, dated August 28, 1900.

Application filed July 27, 1900. Serial No. 25,055. Term of patent 14 years.

To all whom it may concern:

Be it known that I, JAFEW S. VAN BUREN, a citizen of the United States, residing at Albany, county of Albany, State of New York, have invented and produced a new and original Design for Water-Fronts for Stoves, of which the following is a specification, reference being had to the accompanying drawings, forming part thereof.

Figure 1 is a perspective view of a water-front, showing my new design. Fig. 2 is a top view of the same.

The leading or essential feature of my design consists of a projecting flange provided on the water-front, as clearly shown in the drawings, said flange having indentations or scallops.

B represents the main body of my water-front, which is provided with a projecting flange A. In the projecting edge of said flange ²⁰ there are indented a series of scallops *a*.

Having described my invention, what I declare as new, and desire to secure by Letters Patent, is—

The design for a water-front for stoves, as ²⁵ herein shown and described.

In testimony whereof I affix my signature in presence of two witnesses.

JAFEW S. VAN BUREN.

Witnesses:

A. M. BLANCHARD,
GUS MUEHLECK.
